United States Patent Office

Des. 203,173
Patented Dec. 14, 1965

203,173

LADDER

Howard L. Chubbs, 736 Hanley St., Gary, Ind.

Filed Dec. 10, 1964, Ser. No. 82,976

Term of patent 14 years

(Cl. D15—8)

Fig. 1

Fig. 2

Fig. 3

Fig. 4

Fig. 5

FIGURE 1 is a front perspective view of a ladder, showing my design;

FIGURE 2 is a front elevational view; and

FIGURE 3 is a side elevational view thereof.

FIGURE 4 is an enlarged fragmentary view showing the base in greater detail; and

FIGURE 5 is an enlarged fragmentary view showing the top of the ladder in greater detail.

I claim:

The ornamental design for a ladder, as shown.
